Inventor,
Calvin Barber.

United States Patent Office.

CALVIN BAKER, OF ST. JOSEPH, MISSOURI.

Letters Patent No. 94,272, dated August 31, 1869.

IMPROVEMENT IN BRIDGES.

The Schedule referred to in these Letters Patent and making part of the same.

To all whom it may concern:

Be it known that I, CALVIN BAKER, of St. Joseph, in the county of Buchanan, in the State of Missouri, have invented a Plan for the Cheap Construction of Common Road-Bridges, whereby the banks of water-courses are made to form the abutments; and I do hereby declare that the following is a full and exact description thereof, reference being had to the accompanying drawings, and to the letters of reference marked thereon.

My invention consists in supporting inclined thrusting-beams, which connect above the floor and extend below the floor, in sockets which rest on bearings directly against the banks of the stream, whereby a simple and practical device is produced.

The main braces are bolted to the floor-beams, and framed above with king and queen-rods and braces, in any of the known forms. By this simple mode of framing, bridges can be made at reasonable cost, for spans from forty to sixty feet, and as great as one hundred feet, by additional braces between the junction of the main braces and floor-beams. The floor-joists are made to rest upon the beams, and the flooring laid lengthwise with the span.

To enable others skilled in the art to make and use my invention, I will proceed to describe its construction.

I frame on the outside of floor-beams *b*, two main braces, *a a*, these main braces *a a* passing floor-beams *b* at *d d*, and bolted to beam *b* at *d d*, by any of the known forms.

Said main braces *a a* are extended down into iron sockets, *S*, resting on bearer *c c*, which bear evenly on the natural banks of streams, thereby forming a ready and firm abutment.

Above the beam *b*, the main braces *a a* come together, and are framed and secured with socket and queen-rods and king-rod, in any of the known forms, with braces from beam *b* to junction of queen-rods and main braces at *e e*, said king and queen-rods passing through beam *b*, and secured.

To prevent the top of the main braces *a a* spreading, a tie-rod is secured at *f*. The beams *b*, resting on the natural banks, joists *g g* are secured thereon, and the flooring nailed lengthwise with the bridge.

I am aware that truss-bridges have been constructed with auxiliary braces extending below the floor-chords and resting against the vertical or oblique faces of the piers. I therefore do not claim, broadly, the principle of extending the braces below the floor-chords or sills, but the following is what I claim, and desire to secure by Letters Patent:

In combination with the inclined thrusting-beams *a a*, connected at a point, *f*, above the floor, and extending below the floor, the sockets *S S*, resting on suitable bearings directly against the banks of the stream, and employed to receive and support the lower ends of the beams, substantially as described.

CALVIN BAKER.
